UNITED STATES PATENT OFFICE.

JOHN N. WALLACE, OF ANTWERP, BELGIUM, ASSIGNOR TO WESTERN ELECTRIC COMPANY, OF NEW YORK, N. Y., A CORPORATION OF ILLINOIS.

PRINTING-MACHINE.

1,097,203.

Specification of Letters Patent.

Patented May 19, 1914.

Application filed January 31, 1913. Serial No. 745,354.

To all whom it may concern:

Be it known that I, JOHN N. WALLACE, a subject of the King of Great Britain, residing at Antwerp, Belgium, have invented 5 a certain new and useful Improvement in Printing-Machines, of which the following is a full, clear, concise, and exact description.

This invention relates to printing machines and more particularly to apparatus adapted to advance and control the record medium, such as a sheet or strip of paper, which is intermittently fed across the face of the platen as the printing proceeds.

15 The object of this invention is to provide a gripping device which, when actuated, grips the paper, advances it, and then returns to normal position in a separate path, approximately parallel to that taken 20 on its advance movement. There is also provided a holding device which retains the paper in its advanced position after the forward movement.

The improved apparatus as shown, is embodied in a gripping device comprising two 25 principal movable parts, one of which is adapted to advance and close the grip after which both parts are moved upward. The two movements are successive and are at approximately a right-angle with respect to 30 each other. A lever or support is pivoted to afford the required movement, and an electromagnet with its armature retractor is arranged to impart an oscillating movement 35 thereto. This results in a positive advance movement of the paper, a freeing of the gripping device from the paper at the end of the advance movement and a return of the gripping device to normal position with 40 no danger of buckling the paper on the return movement thereof.

This invention will be fully understood from the following description taken in connection with the accompanying drawing in 45 which,—

Figure 1 is a perspective front elevation showing a single grip arranged to engage the paper sheet at its center; Fig. 2 is a side elevation showing the parts in normal position; and Fig. 3 is the same view but showing the parts at the end of an advance step.

A paper carriage 10 is adapted to move to and fro on a track 11 on which its grooved

wheels 12 travel. An upper rail or track 55 13 is provided to retain the carriage 10 against excessive lateral or vertical displacement. The carriage 10 supports a guide 14, held by depending lugs 15, which serves to guide a record medium or paper 60 sheet 16. The guide 14 is limited in its downward movement by a wire or rod 17. The gripping mechanism is composed of a gripping device 18 and a pivoted member 19. The grip 18 is pivoted at 20 and has a 65 sharp surface at one end, shown as a tooth 21, for insuring a firm hold on the paper. The member 19 is pivoted at 22 to a lug 23 supported on the frame 24 of the machine. The member 19 is subjected to the tension 70 of a retractile spring 25 which tends to hold the member in its normal position as shown in Fig. 2 and is provided with a hard rubber contact surface 26 between which and the tooth 21 the paper 16 lies and is gripped 75 at intervals to impart advance movement thereto. The grip 18 is adapted to be advanced in a horizontal line, gripping the paper 16 between the tooth 21 and the rubber surface 26, and then to be moved up- 80 ward in a substantially vertical line rotating the member 19 about its pivot 22 and advancing the paper sheet 16. The limit of the advance movement is shown in Fig. 3. The grip 18 is then freed and together with 85 the member 19 assumes the normal position as shown in Fig. 2.

The means for producing the desired movements comprises a pivoted supporting member and an electromagnet for controlling the movement of the same. This device is shown as a two-armed lever 28 pivoted on bearings 29. The lever 28 has a downwardly projecting arm 30 and a laterally projecting arm 31. The arm 30 carries an armature 32 of an electromagnet 33, and the lever 28 and armature 32 are normally retracted by a spring 34 into the position shown in Fig. 2. The arm 30 is preferably connected to grip 18 by an arm 35 100 which is slotted at 36 and is united to arm 30 by the pivot screw 20. A set screw 38 with its lock nut is employed to adjust the extent of movement of this slot connection. The opposite end of the arm 35 is connected 105 to the grip 18 by screws 39. A spring 40 connects a point 42 on the arm 31 with a point 43 on the arm 35 above the central

plane thereof, which tends to separate the free ends of arms 31 and 35. This construction insures the approximate horizontal movement of the grip 18 until the tooth 21 engages the paper strip 16 against the member 19. The laterally projecting arm 31 of lever 28 carries a lever-like member 50 pivoted thereto at 51. A set screw 54 provided with a suitable lock nut serves to adjust the extent of movement of lever 50 about its pivot 51. The outward end of the member 50 is pivoted at 55 to a link 56 which is provided with a long slot 57 adapted to engage a pin 58 on the grip 18.

15 The lower end of the arm 30 is positioned to engage a contact spring 59 when the armature 32 has been attracted by the electromagnet 33 far enough to properly advance the paper. The contact spring 59 normally rests in engagement with a contact spring 60 which together with spring 59 forms the normally closed terminals of a break in the circuit energizing the electromagnet 33. When, however, the paper has been properly advanced the lower end of arm 30 opens the circuit between springs 59 and 60, causing the electromagnet to become deenergized which allows the retractile springs 25, 34 and 40 to return the mechanism to normal position.

In operation the electromagnet 33 is energized when the carriage 10 has been retracted to the starting end of a line of print in which position the gripping device will engage the record medium approximately on the center line thereof. The armature 32 is thereupon attracted moving the two-arm lever 28 about its pivot 29. The arm 31 consequently rises and through the agency of spring 40 draws the arm 35 to the right in approximately a horizontal line so that the paper is gripped between tooth 21 and the surface 26. The arm 30 moves screw 20 toward the righthand end of slot 36 allowing the retractile force of spring 40 to advance the arm 35 and grip 18 with its tooth-like projection 21. When the paper strip 16 is firmly held between tooth 21 and surface 26 the member 50 raising with the arm 31 brings the lower end of slot 57 into engagement with pin 58 in grip 18, and both grip 18 and member 19 rise from the position shown in Fig. 2 to that shown in Fig. 3. The paper is thus advanced the space between successive lines of print. As the arm 30 reaches the limit of its movement, its lower end separates contact springs 59 and 60 as hereinbefore described and the magnet 33 is deenergized. The spring 34 thereupon retracts the armature 32, link 56 descends freeing the grip contact 18 so that it may descend, and as the movement continues grip 18 is withdrawn from engagement with the paper 16 and the parts resume their normal position

as shown in Fig. 2. The grip 18 has now engaged the paper, advanced the paper, retracted and returned to normal position.

To retain the paper against any tendency to recede from its advanced position, a ball 70 is provided. The ball 70 is located in a housing 71 having an inclined wall 72 and a vertical wall 73. The paper 16 passes through this housing between the ball 70 and wall 73. The ball 70 controlled by gravity jams the paper 16 against wall 73, but when the paper 16 is moved upward by the paper feed hereinbefore described, the ball 70 is carried upward by engagement with the paper, along the inclined wall 72. This frees the paper and allows it to move upward in response to the effort of the gripping mechanism.

What I claim is:

1. In a printing machine, a paper feed including a gripping device adapted to move in two directions, successively, at an approximate right-angle, in combination with a device for supporting link connections, link connections between pivotal points on said supporting device and said gripping device, and an electromagnet for actuating said supporting device whereby said supporting device causes said grip to engage the paper, advance the paper, retract, and then return to normal position in the order named.

2. In a printing machine, a paper feed including a grip adapted to move in two directions, successively, at an approximate right-angle, in combination with a two-armed lever, slotted link connections between said gripping device and said arms, respectively, a spring connecting one arm of said lever and the link connection of the other arm, and means for actuating said lever.

3. In a printing machine, means for advancing the record medium, consisting of a pair of movable engaging contacts, in combination with a two-armed pivoted, angular lever, a link connected to one arm of said lever by a slotted bearing and at its opposite end pivoted to one of said contacts, a member pivotally supported on the other arm of said lever, a slotted link having one end pivotally connected to said member and its slotted end connected to a point on said contact, with an electromagnet arranged to oscillate said two-armed lever on its pivot.

4. In a printing machine, a paper feed including a gripping device composed of two movable engaging contacts, one of which is adapted to move in two directions, at an approximately right-angle, successively, in combination with a two-armed pivoted lever, a link connected to one arm of said lever by a slotted bearing and at its opposite end pivoted to one of said contacts, a member pivotally supported on the other arm of said lever, a slotted link having one end pivotally connected to said member, its slotted end

- connected to a pivot on said contact, a spring connecting one arm of said lever and the link connection of the other arm, and an electromagnet arranged to oscillate said lever.
- 5 5. In a paper feed for a printing machine, the combination with means for advancing the paper, of separate means for retaining said paper at each step, consisting of a fixed wall, a ball or roller, a housing for said ball
- 10 10 having a wall fixed at a converging angle with respect to the first wall, and a passage for the paper between the ball and the first named wall.

6. In a paper feed for a printing machine, the combination with means for advancing 15 the paper, of means for retaining said paper against return movement, including a ball or roller, and a housing for the ball through which the paper passes.

In witness whereof, I hereunto subscribe 20 my name this 17th day of December A. D., 1912.

JOHN N. WALLACE.
